FINGER RING ENSEMBLE

Roy B. Keehnel and Nadine Keehnel, Independence, Mo., assignors of fifty per cent to Benjamin B. Franklin, Kansas City, Mo.

Application April 19, 1937, Serial No. 137,681

4 Claims.

(Cl. 63—15)

This invention relates to improvements in finger rings and has particular reference to finger ring ensembles.

The principal object of the invention is the provision of two separate and complete rings, which are adapted to be worn separately or in fixed assembled relation, whereby they present the appearance of a unitary structure.

Another object of the present invention is the provision of a ring ensemble, wherein two rings of like internal diameters are so nested together as to prevent relative movement thereof when they are in position on the finger of the wearer.

A further object of this invention is the provision of a finger ring ensemble, wherein a primary ring is provided with a slot and recess for the reception of a secondary ring, and cover means for closing said slot in said primary ring when said secondary ring is removed therefrom.

Another object is the provision of a finger ring ensemble, wherein the inserted ring is a set ring, such as a diamond engagement ring, while the primary ring may be the usual band-shaped wedding ring, slotted and grooved to receive said set ring with the set thereof protruding at the top of the ensemble.

Other objects are simplicity and economy of structure, ease of assembly, and a symmetrical arrangement of the parts.

Reference will now be had to the drawing, wherein:

Fig. 1 is a side elevation of a ring ensemble embodying this invention.

Fig. 2 is a plan view of the ring ensemble.

Fig. 3 is a side elevation.

Fig. 4 is a diametrical sectional view, taken on line IV—IV of Fig. 1.

Fig. 5 is a side elevation of the primary ring, with the secondary ring removed therefrom.

Fig. 6 is a section taken on line VI—VI of Fig. 5.

Fig. 7 is a side elevation of the secondary or set ring.

Fig. 8 is a plan view of the primary ring.

Fig. 9 is a plan view of the primary ring, with the cover member in position.

Fig. 10 is a vertical, sectional view, taken on line X—X of Fig. 9.

Fig. 11 is an elevation of the cover member, and,

Fig. 12 is a sectional view, taken on line XII—XII of Fig. 11.

Like reference characters designate similar parts, and the numeral 10 indicates the primary ring or annulus, of a form suitable for a wedding

ring. The outer surface of said ring may be engraved or otherwise embellished to produce the desired appearance. Ring 10 is provided with a suitable slot 12, which is substantially semi-circular, and shaped to conform to the shape of the secondary ring 14, which is adapted to be fitted therein in a manner hereinafter described. The inner wall 16 of ring 10 is provided with a groove 18, which is of an extent sufficient to interconnect the opposite ends of slot 12. This groove may be of uniform cross section, tapered or otherwise shaped to conform to the secondary ring.

Referring to Figs. 1 and 4, wherein the primary and secondary rings are shown in the nested relation, it will be noted that the annular openings therethrough are concentric so that the finger of the wearer can be inserted therethrough to maintain the rings in this registered relation. To avoid relative rotary movement of the nested rings, a groove 20 is formed in the side wall of slot 12 and is adapted to receive ribs 22 formed on the side walls of the secondary ring 14. These grooves and ribs as shown are so positioned in the ring members respectively that they permit of the insertion of the secondary ring on the diametrically disposed line so that when the two rings are nested together, the set 24 of the secondary or engagement ring will be positioned outside the outer periphery of the primary ring, while that portion of the secondary ring opposite the set will be nested in groove 18 of the primary ring. It is very apparent that with this structure, wherein the ensemble consists of a relatively wide wedding ring and a narrower engagement ring, it is possible to nest these rings together so that both the rings will be visible when the ensemble is placed on the finger in the usual manner, with the set located at the outside of the hand.

When the primary ring is to be worn alone, it may be rotated on the finger so that the slot formed therein will be on the inside of the hand. Also, a filler 26 is provided for filling the slot in the primary ring, which consists of a semi-circular band, made to substantially conform to the outer contour of the slot 12, and provided with a resilient fastener 28, which is adapted to be snapped into position in grooves 20, which are slightly undercut, as clearly shown in Figs. 4 and 10. The outer surface of filler 26 may be provided with sets or may be otherwise decorated.

In view of the fact that the engagement ring 14 is the first acquired, it will be a complete and definite unit, suitable for wearing inde-

pendently of any other ring, and when the wed-
ding ring is obtained, it is the intention that
the engagement ring be nested therein and worn
as shown in Figs. 1 and 2, thereby presenting a
5 visible display of both rings on the top of the
finger and also precluding the usual wear of the
two rings experienced when they are worn side
by side with no definite connection therebetween.

While but one form of primary and secondary
10 rings has been shown, yet it is apparent that
many changes might be made in either or both
of these rings without departing from the salient
features of this invention. Also, the means de-
scribed for preventing relative rotation of the
15 assembled rings might be differently positioned
and shaped if it is found advantageous for pur-
poses of decoration or construction.

What we claim is:

1. A finger ring ensemble comprising a pri-
mary band ring slotted transversely to its axis,
20 and provided with an internal groove intercon-
necting the opposite ends of said slot; a secondary
set ring removably mounted in said primary ring
with a portion thereof resting in said groove
25 and with the said set positioned beyond the out-
side periphery of the primary ring; and inter-
locking means formed on the primary and sec-
ondary rings to prevent relative rotation of the
rings.
- 30 2. A finger ring ensemble comprising a primary
ring slotted transversely to its axis, substantially

half way therearound, and having a groove
formed in the inner wall thereof to interconnect
the opposite ends of said slot; a secondary ring
adapted to be positioned through said slot with
its inner portion in said groove whereby the inner
circumferences of the two rings coincide; and
interlocking means securing said nested rings
against relative rotation.

3. A finger ring ensemble comprising a primary
band ring slotted transversely to its axis, and 10
provided with an internal groove interconnect-
ing the opposite ends of said slot; an offset formed
in the side wall of said slot; and a secondary
set ring removably mounted in said primary ring
with a portion thereof resting in said groove and 15
with the said set positioned beyond the outside
periphery of the primary ring, and a projection
formed on the side wall of said secondary ring
adapted to engage said offset to prevent relative
rotary movement of the rings. 20

4. A finger ring ensemble comprising a primary
ring slotted transversely to its axis, substantially
half way therearound, and having opposed
grooves formed inwardly from the edges of said
primary ring at the slot midway between the ends 25
thereof; and a filler having fastening means en-
gaging said grooves whereby it is releasably se-
cured in position to cover said slot in the pri-
mary ring.
